UNITED STATES PATENT OFFICE.

WILLIAM C. VOGEL AND HARRY K. SNELL, OF ROCKFORD, ILLINOIS.

PIANISSIMO DEVICE.

No. 846,071.

Specification of Letters Patent.

Patented March 5, 1907.

Application filed January 6, 1906. Serial No. 294,897.

To all whom it may concern:

Be it known that we, WILLIAM C. VOGEL and HARRY K. SNELL, citizens of the United States, residing at Rockford, in the county of Winnebago and State of Illinois, have invented a new and useful Improvement in Pianissimo Devices, of which the following is a specification.

This invention is an improvement upon an upright-piano action for which we were granted Letters Patent February 13, 1906, No. 812,705.

The object of this invention is to permit a closer adjustment by employing two capstan-screws and by permitting an upward and forward movement of the lever-rail, thus reducing friction.

With this object in view our invention consists in the novel features of construction and combination of parts hereinafter set forth, pointed out in the claims, and shown in the accompanying drawings, in which—

Figure 1 is a vertical section through the piano, showing the parts in their normal positions with certain parts omitted. Fig. 2 is a similar vertical section with additional parts, showing the position of the movable parts while the key is at rest and the soft pedal is depressed. Fig. 3 is a detail perspective view showing portions of the lower part of the action and illustrating the connection between the key and the movable parts of the action. Fig. 4 is a detail front perspective view of a portion of the action shown in Fig. 3. Fig. 5 is a detail perspective view of an action-bracket, showing the rear side of the said bracket. Fig. 6 is a detail perspective view of a portion of a lever-rail, showing a double hinged bracket secured thereto and connecting-arms adapted to connect the said bracket to the action-bracket shown in Fig. 5. Fig. 7 is a transverse sectional view through the action-bracket and showing a portion of the lever-rail in plan and illustrating the manner of hinging said lever-rail to the action-bracket. Fig. 8 is a detail perspective view of a hinge and a bent bar, the two being detached. Fig. 9 is a detailed perspective view of an adjustable bracket, of a covering for same, and a thumb-screw, the parts being detached. Fig. 10 is a detail perspective view of a lever-rail hanger. Fig. 11 is a vertical section through the hanger shown in Fig. 10 and showing the bracket of Fig. 9 in position in

the hanger, the bracket-covering being in place and shown in section. Fig. 12 is a perspective view of a pilot-bar. Fig. 13 is a detail perspective view of a lever and a capstan-screw detached. Fig. 14 is a detail perspective view of a flange. Fig. 15 is a side elevation, partly in section and enlarged, showing a lever key, and capstan-screw. Fig. 16 is a detail side elevation showing a portion of the lever and the lower end portion of a pilot-bar and showing the capstan-screw inverted. Figs. 17, 18, and 19 are side elevations, partly in section and showing modifications of the capstan-screws and their relative positions. Fig. 20 is a perspective view showing a modification.

In the drawings, A represents the main action-rail, provided with an upwardly-extending flange A' and a depending flange A''. The action comprises a number of parts common to all piano-actions and which are shown and described in applicants' Patent No. 812,705, dated February 13, 1906. The very brief references to these portions will therefore be sufficient, and it will therefore be understood that the flange A' carries a hammer-butt B, to which is connected a hammer C, having a hammer-head C'. The main action-rail A is also provided with a rearwardly-extending flange A'', to which is pivoted a damper-lever B'', carrying a damper B''' and provided with a restoring-spring B''. To the flange A'' is pivoted a whip B', which carries a spoon B'' in engagement with the lower end of the damper-lever B''. The upper end of a pilot D is pivoted to the whip B', and the whip B' is connected to the hammer-butt B by a bridle B⁸ and bridle-wire B⁹. A cushioned hammer-check B⁶ is supported from the whip B', the said hammer-check operating with a buffer B⁷, supported from the hammer-butt B. A movable hammer-rest C² is connected by hammer-rail hooks C⁴ to a vertical action-bracket C³, so that the hammer-rest rail can be moved toward and away from the strings Q, the movement of the hammer-rest rail being effected by means of a soft-pedal rod C⁵, the upper end of which is secured in the usual manner to the hammer-rest rail. The lower end of the vertical action-bracket C³ is provided with the usual foot portion, and this portion has its upper horizontal face cut away, as shown at C⁶, for a purpose to be hereafter explained. Adjacent its lower end the perforations C⁷ are formed in the ver-

tical action-bracket in vertical alinement with each other, and these perforations are bushed with cloth.

Upon the rear edge of the vertical action-bracket are formed two oppositely-extending lugs L, and immediately below these lugs is formed a shoulder L', the upper face of which is recessed or cut out, and extending from this shoulder L' downwardly to the foot of 10 the action-bracket is a vertical strengthening-rib C⁸.

The lower end of the pilot D is bifurcated and fits over and is pivoted to a lever E, and a capstan-screw E', provided at one end with 15 a removable round head E², passes outwardly and in a rearwardly-inclined direction through a perforation E³, formed diagonally through the lever E. A key E⁴ is provided adjacent its rear end with a felt portion E⁵, 20 upon which the head of a capstan-screw E' bears. The key also rests upon a suitable cushion E⁶, as shown in Figs. 1 and 2. Upon the key E⁴ and in advance of the felt portion E⁵ is placed vertically a capstan-screw E⁷, 25 and upon the forward under face of the lever E is placed a cushion of felt or other suitable material E⁸, which rests upon the head of the capstan-screw E⁷.

The piano-action also comprises a regulating-rail F, which is arranged in advance of 30 the main action-rail A and which carries an adjustable regulating-button F'. A jack G is pivotally supported from the whip B', and a coil-spring G' bears at its upper end upon 35 the toe of the jack G and at its lower end upon the face of the whip B'. The button F' can be adjusted so that when the jack G is actuated by movement of the whip B' the toe of the jack will press upon the button F', thus 40 relieving the hammer-butt of the pressure, but at the same time permitting the jack G and the hammer-butt B to remain in such relative positions to each other that the hammer C will quickly respond to any movement 45 of the jack.

A vertically-movable lever-rail H carries a depending flange H', which is slightly longer than the usual flanges carried by lever-rails, and it is of course understood that the flange 50 H' is bifurcated at its lower end, and in this bifurcation is pivotally held the rear end portion of the lever E, so that any upward movement of the lever-rail H will also elevate the rear end of the lever E, and thereby change the 55 relative position of the capstan-screw E' to the key E⁴. The lever-rail H is secured to the vertical action-bracket C³ by means of the following-described mechanism: A plate H² is secured to the front face of the lever-rail H, 60 and this plate carries projecting shoulders or lugs at its upper and lower ends, and said shoulders are provided with perforations suitably bushed with cloth. Links H³ have their end portions bent in opposite directions, 65 and the bent end portions of the rear ends of

the hooks are inserted into the perforations of the shoulders of the plate H², and the bent portions at the forward ends of the hooks engage the bushed perforations C⁷ of the vertical action-bracket C³. By means of this 70 construction the lever-rail H is given a compound movement, rising and falling vertically, and also moving as it rises toward the vertical action-bracket C³ and as it falls moving away from the said bracket. The front 75 lower edge of the lever-rail H is beveled, and where the said rail rests when in its normal position upon the foot or shoe of the vertical action-bracket C³ it is cut, out and a block H⁴ is inserted in the cut-out portion, and a 80 suitable cushion H⁵ is secured to the under face of the said block and also extends transversely across the beveled portion of the lever-rail, and this cushion H⁵ bears upon the cut-out portion C⁶ of the foot of the vertical action-bracket. 85

A bracket J is provided with a plurality of longitudinal slots J' and also at its rear end with parallel perforated lugs, and this bracket is secured to the under face of the hammer-rest rail C² by means of screws passing through the slots J'. By loosening the screws the plate J can be moved upon the under face of the hammer-rest rail a distance substantially equal to the length of the slots, 90 and the bracket is therefore adjustable with respect to the hammer-rest rail. A bar K has its central portion K' offset with respect to its upper and lower ends, and the upper end of the said bar is pivoted between the 100 lugs of the bracket J. The lower end of the bar K is adjustably and loosely connected to the hammer-rest rail in the following manner: A lever-rail hanger K⁸ is secured to the lever-rail, and this hanger comprises an angle-plate having parallel upwardly-extending lugs K⁹, connected by a cross-piece K¹⁰, the under side of which is rounded. A block K² is vertically slotted, as shown at K³, and is also provided with a perforation leading into 105 said slot and through which works a set-screw K⁴. The block carries a rearwardly-extending arm K⁵, having a curved portion K⁶, which rests between the lugs K⁹ of the hanger K⁸, and which engages the round 110 face of the cross-piece K¹⁰. To make the operation of the arm noiseless, it is covered with a flexible shield K⁷ of any suitable cushioning material. The lower end of the bar K passes through the slot K³ and is 115 locked in the same in its adjusted position by means of set-screws K⁴.

The lifting of the hammer-rest rail C² from its normal position to that shown in Fig. 2 and consequent vertical movement of 125 the bar K will impart an upward movement to the lever-rail H. The offset in the bar K (shown at K') enables the said bar to clear the regulating-rail F.

In Figs. 17, 18, and 19 we have shown a 130

modification in the construction and arrangement of the capstan-screws, it being understood that other parts are substantially the same. In Fig. 17 a lever M is provided upon its under face with two capstan-screws M', which are adapted to be acted upon by a cushion M², carried by a key M³. Fig. 18 shows the same parts, the changes lying in the fact that a lever O carries a cushion O', which is engaged by capstan-screws O², carried by a key O³. The same parts are again shown in Fig. 19, and in this last modification the lever P carries a cushion P' and a capstan-screw P², and the key P³ carries a capstan-screw P⁵, which coöperates with the cushion P' and also carries a cushion P⁴ coöperating with the capstan-screw P². In all of these arrangements the same result is aimed at—that is, the maintaining of the keys in their normal position when the soft pedal is depressed—whereby the key has the same sweep or limit of travel in rising and falling when the soft pedal is depressed as it has when said pedal is not in use, and this uniformity and certainty in the movement of the key adds to the certainty of the touch on the part of the performer and there is the same amount of fall in the finger movement when the soft pedal is depressed as when it is not in use. By means of the adjustability of the plate J any lost motion in the mechanism can be readily taken up.

The operation of the parts in common use in piano-actions will be fully understood, and the operation of the novel portions of the mechanism is as follows: When the soft pedal is depressed, the soft-pedal rod C⁵ rises and the hammer-rest rail C² is moved upwardly and toward the strings Q into the position shown in Fig. 2, thereby limiting the movement of the hammer C. This movement of the hammer-rail C² upwardly and also rearwardly toward the strings Q carries the bar K with it, and as this bar is connected in the manner described to the lever-rail H the said rail is also lifted vertically, and by means of the links H³, which pivotally connect the lever-rail H to the vertical action-bracket C³, the lever-rail H moves forwardly as well as vertically. This upward and forward movement of the lever-rail H lifts the rear end portion of the lever E and lifts the capstan-screw E' out of contact with its cushion E⁵, and the lever E at its forward end rocks upon the slightly-rounded head of the capstan-screw E⁷. The key E⁴ in the meantime remains in its normal position, and when the key is depressed by the finger its rear end is lifted, and by reason of the engagement of the capstan-screws E⁷ with the cushion E⁸ the lever E is lifted at its forward end, thereby lifting the pilot D and actuating the whip B and connected parts.

It will be understood, of course, that immaterial changes in the relative arrangement

and sizes of the various parts can be made in order to accommodate the action to pianos of various sizes and case designs without changing the manner of operation or the results gained.

In Fig. 20 we have shown the lever E pivotally hung in the slot D' of the pilot-rod D², and the cushion D³ is carried by the lower end of the pilot-rod. A key Q carries a cushion Q', which is engaged by the head of the capstan-screw R. A capstan-screw S is also carried by the key Q in position to engage the cushion D³, carried by the pilot-rod.

Having thus fully described our invention, what we claim, and desire to secure by Letters Patent, is—

1. In a piano-action the combination with a vertical action-bracket, of a lever-rail, links pivotally connecting the said lever-rail to the said vertical action-bracket, a hammer-rest rail, adapted to be moved upwardly and rearwardly and connecting means between the hammer-rest rail and the lever-rail adapted to lift the lever-rail upwardly and forwardly during upward and rearward movement of the hammer-rest rail.

2. In a piano-action a vertically-movable lever-rail, a lever pivotally suspended at its rear end from said rail, a pilot pivoted at its lower end to an intermediate portion of the said lever, a capstan-screw carried by the lever in advance of the pilot, a key, and a capstan-screw carried by the key in advance of the screw carried by the lever the screw on the lever engaging the key and the screw on the key engaging the lever, as and for the purpose set forth.

3. In a piano-action an upwardly and forwardly movable lever-rail, a movable hammer-rest rail, an adjustable plate carried by said last-mentioned rail, a bar pivotally connected to said plate, means for loosely connecting the lower end portion of said bar to the lever-rail, a key, a pilot, a lever pivotally connected to the pilot intermediate its ends, and pivotally suspended from the lever-rail adjacent its rear end, and a plurality of capstan-screws adapted to coöperate with the said key and lever.

4. In a piano-action a vertical main action-bracket having a foot portion at its lower end, said foot portion being cut away on its upper face, a rib on the rear face of the vertical action-bracket, the said bracket being perforated adjacent the foot, the lever-rail, a plate carried by said lever-rail and having perforated shoulders at its ends, links having hooked members engaging respectively perforations in the shoulders of the plate and perforations in the action-bracket, said links being arranged in pairs and upon opposite sides of the rib, a block inserted in the rear face of the lever-rail, the said lever-rail being beveled along its lower front edge, and a cushion carried by said block and a portion

of the beveled edge and adapted to rest in the cut-out portion of the foot.

5. A device of the kind described comprising a movable hammer-rest rail, a lever-rail, a lever-rail hanger, a vertically-slotted block, an arm carried by the block and having a curved portion loosely engaging the lever-rail hanger, and a bar adjustably held in the slot of the block and pivotally supported 10 from the hammer-rest rail.

6. In a piano-action a movable hammer-rest rail, a plate adjustably carried by said rail, a bar having its central portion offset with respect to its end portions and having 15 its upper end pivotally connected to said plate, a lever-rail, a lever-rail hanger, a slotted block, an arm carried by the block and loosely in engagement with the lever-rail hanger, the lower end portion of the bar passing 20 through the slot of the block, means for locking the said bar to the block, and means

for pivotally connecting the lever-rail to the vertical-action rail of a piano.

7. The combination with a vertically-movable lever-rail, an angle-plate secured thereto, parallel lugs carried by said plate, a cross-piece connecting said lugs and having a round under face, a block, an arm carried by the block and having a curved end portion adapted to rest between the lugs of the plate and 25 beneath the cross-piece, a flexible sleeve carried by the curved portion of said arm and adapted to engage the cross-piece, a movable hammer-rest rail, a bar pivotally supported therefrom, and means for connecting said 30 bar to the said block. 35
